LIQUID TANK FOR RUG AND FLOOR CLEANING AND WAXING MACHINE

Alexander B. Musichuk, Tallmadge, Ohio, assignor to
The Hoover Company, North Canton, Ohio, a corporation of Ohio

Filed Apr. 29, 1960, Ser. No. 60,367

Term of patent 14 years

(Cl. D9—2)

Fig. 2

Fig. 1

Fig. 3

FIGURE 3 is a side elevational view thereof, and the opposite side is substantially the same as that shown,

The dominant features of my design reside in the portions shown in full lines.

I claim:

The ornamental design for a liquid tank for rug and floor cleaning and waxing machine, substantially as shown and described.
